FILTER REPLACEMENT CONSTRUCTION
FOR VACUUM CLEANERS

Edgar P. Senné, Rockville Centre, N. Y.

Application February 18, 1948, Serial No. 9,047

2 Claims. (Cl. 183—43)

1

This invention relates to improvements in air filter machines, for example, vacuum cleaners either of the relatively fixed position type or of the type adapted to be freely and easily propelled over a floor in any desired random direction by small manual forces applied by a domestic user, such as those of the type disclosed and claimed in my pending applications Serial No. 749,772 filed May 22, 1947 and Serial No. 702,389 filed October 10, 1946.

It has for its principal object the provision of an improved filter containing unit permitting the convenient and ready insertion or removal of a preferably dispensable filter, such as a dirt or dust collecting bag of paper, cloth or like material—all with the view to enhancing the ease, speed and convenience with which a domestic user may perform the operation of replacing the filter.

The features of the invention on which patent protection is sought are set forth in the appended claims. The invention itself, together with further objects and advantages thereof may best be understood by reference to the following specification and accompanying drawings illustrating a preferred embodiment of the invention.

In the drawings:

Fig. 1 is a plan view of what may be termed the front face of the machine;

Fig. 2 is a transverse cross-section of the machine taken along the line 2—2 of Fig. 3;

Fig. 3 is similarly a longitudinal cross-section taken along the line 3—3 of Fig. 1 and showing the internal elements within the chassis thereof with the filter holding means in closed position;

Fig. 4 represents in cross-section a partial view of the filter compartment showing the filter insertion and removal means in their open position;

Fig. 5 illustrates a sectional view of the structure of the chassis taken along the line 5—5 of Fig. 2;

Fig. 6 illustrates a view of the filter clamping means as seen from the line 6—6 of Fig. 3; and

Fig. 7 illustrates, in perspective, a view of one type of filter bag unit which may be used in the machine.

Although the invention may be embodied in any type of machine, whether mobile or relatively stationary and whether having relatively movable chassis and support means or not, it is illustrated as embodied in the mobile type of my aforesaid applications having relatively movable chassis and mobile support means therefor.

2

The general structure of the machine may best be visualized from the Figures 1 through 3. As therein illustrated, it may comprise generally a chassis 1 of roughly cylindrical outline and supported by two large wheels 2 and 3 mounted on the ends of a transverse shaft or axle 5 and for free rotation about the axis thereof. These wheels are preferably domed outwardly on either side of the chassis and the annular shell of the chassis, between the wheels, is preferably correspondingly rounded so that, with the exceptions noted below, the entire machine represents the general appearance of a sphere. The configuration thus presented is convenient for preventing interference with obstructions such as furniture and rugs which might be encountered during motion of the machine over a floor and in addition presents a somewhat pleasing appearance. The wheels 2 and 3 have annular rim portions 6 projecting outwardly from the general contour and terminating in the circular treads 7.

The chassis 1 is divided by a transverse partition or wall 8 into a filter compartment 9 above the axle 5 and an air propulsion compartment 10 therebelow, the center of gravity of the chassis being below the axle 5 whereby the wall 8 will normally assume a horizontal position when the chassis is freely suspended. The filter compartment is adapted to contain a filter 11 (Fig. 7) which is preferably in a form of a bag of cloth or like material; while within the air propulsion compartment there is provided any suitable air propulsion means illustrated generally by the motor-fan unit 12. In order to permit ready ingress of air to be filtered into the filter compartment, a suitable inlet in the form of the tubular intake manifold 13 may be provided, the manifold having an inlet orifice 14 in the external shell of the filter compartment and an outlet orifice 15 in juxtaposition to or alignment with the mouth of the filter bag. Manifold 13 is adapted to receive a portable hose (not shown) of the type common in vacuum cleaner practice. Similarly, in order to provide for egress of air from the air propulsion compartment after its passage through the filter bag and through the perforated section 16 of the partition 8, there may be provided a suitable outlet orifice 17 in the external wall of the air propulsion compartment. Preferably the outlet orifice 17 is partially closed by the hinged gates 18 and 19 of open mesh construction in order that they may impede the passage of sizable destructive objects and yet at the same time permit free flow of the filtered air.

It will be understood that the air propulsion unit 12 may be energized by any suitable means, such as a domestic power supply source, although for convenience of illustration and in view of the fact that such means are readily known to those skilled in the art, the circuit connections therefore are omitted. A suitable switch for closing such a circuit may be provided and I have shown that as taking the form of the off-on switch 20 which may be turned off or on by successive depressions of an actuating plunger 21. The plunger 21 may be actuated in this manner by clockwise rotation of the chassis (as seen from Fig. 3) until the plunger 21 is brought into contact with the floor or other relatively stationary surface. These actuations may be accomplished by simple manual manipulation of the chassis by the user. Arrangements of this character whereby the motor may be alternately energized and de-energized by successive actuations of a switch in response to relative movement between parts of the vacuum cleaner, or between the cleaner and floor, effected by successive manipulations of a portable hose affixed to the cleaner are disclosed and claimed broadly in my co-pending application, Ser. No. 67,498, filed December 27, 1948 and entitled Vacuum Cleaner On-and-Off Switching Devices.

The structure thus far described is substantially that disclosed and claimed in my aforesaid applications. The improvements of the present invention will now be outlined in greater detail.

As best indicated by Fig. 2, the chassis is formed by means of two generally circular side plates 22 and 23 held in fixed position by a generally cylindrical structure comprising the curved outer portion 24 and the radially extending side walls 25 and 26 which are rigidly affixed to the side plates 22 and 23 except for those portions forming the side walls of the hinged cover or door hereinafter to be discussed. Preferably the side walls of plates 22 and 23 are provided with the bulbous portions 27 and 28 conforming to the general contour of the counter-part portions of wheels 2 and 3. The circumferential portions of the side plates 22 and 23 extend almost, but not quite, to the rims 7 and preferably are aligned with the inner edges thereof.

For the purpose of removal of the filter 11 from the filter compartment 9 and also for providing a convenient locking means for securing the filter in position, there may be provided a suitable hinged door mechanism formed in a peripheral sector of the outer portion 24. As indicated best by the Figures 3 and 4 this door 29 may include inwardly extending radial side walls 30 and 31 aligned with the side walls 25 and 26 but made movable with respect thereto and with respect to the side plates 22 and 23 in order that the door may be opened. The door 29 is provided with a transversely extending hinge 32 in the outer wall of the compartment 9 and also with a suitable latching means 33 for locking it in its closed position. The locking means 33 is shown as comprising, for example, a manually rotatable bolt 34 affixed to an extension 35 of the door structure and provided with a locking key 36 for keying into a receiving groove 37 of a socket 38. The extension 35 may be provided by a bar strip 39 extending along the periphery of the door 29 and bridging a depression 40 therein in order that it may form a convenient handle for lifting and transporting the machine. On the inward edges of each of the inwardly extending wall portions 30 and 31 there may be provided flange or cam

surfaces 41 which engage the vise mechanism presently to be discussed for the purpose of rigidly securing the same.

For the purpose of rigidly securing the filter 11 within the compartment 9, a suitable vise mechanism may be provided and I have shown a preferred type as comprising the transversely extending fixed wall 42 subtending a sector of the compartment 9, and a hinged clamping member 43 formed of a base 43a and upwardly extending side arms 43b and 43c (Fig. 6). The wall 42 may be affixed at its opposite ends to the partition 8 and the outer wall portion 24. The hinged clamping member 43 may be hinged to the partition 8 by hinges 44 and arranged so that it may be limited in its rotary movement to motion between the positions shown in Figs. 3 and 4 respectively. The wall 42 is provided with an orifice aligned with the orifice 15 of the inlet manifold 13 and an inlet orifice 45 in a collar 46 of the filter bag construction (Fig. 7). Preferably, resilient gaskets 47 and 48 (Fig. 6) of suitable material such as sponge rubber are provided about the orifice on wall 42 and about the edges engaging collar 46. These aid in the firm engagement of the latter by the vise mechanism.

As illustrated in Fig. 7 the filter bag construction may for purposes of cooperation with the vise mechanism be formed of a collar 46 to which the cloth bag filter 11 is affixed and which holds open the neck or mouth of the bag. The collar 46 is adapted to be inserted between the cooperating members of the vise mechanism, i. e. between member 43 and wall 42. In that position the orifice 45 is aligned with the corresponding orifices in the vise mechanism and with the intake manifold while the gaskets tend to seal the passage to escape of air from its intended route into filter 11.

It will be apparent that in the normal operation of the device the filter bag 11 together with its retaining collar 46 may be quickly and conveniently removed and replaced by opening of the door 29. At the same time, when the machine is in normal operation and the door 29 closed, the flange surfaces 41 will firmly engage the clamping member 43 and force it into firm engagement with both the fixed wall 42 and the collar 46 thereby insuring that the filter bag will be held firmly in position during normal operation. In the later position, collar 46 will be between wall 42 and member 43, parallel to the former, with the cloth bag of compartment 9.

It will also be observed that the arrangement has the particular advantage that the filter bag may be replaced without dismantling any parts of the machine proper, nor even disconnecting the hose from the intake manifold.

It will be understood that the invention is not limited to any particular embodiment or any particular arrangement of the parts as hereinbefore outlined and that numerous modifications falling within the scope of the appended claims will occur to those skilled in the art.

What I claim is:

1. A vacuum cleaner comprising a chassis and a mechanism adapted for the insertion and removal of a filter bag within and from said chassis comprising a door within the outer wall of said chassis adapted to be rotated outwardly from the body of said chassis, a vise mechanism for holding said filter bag within said chassis comprising a first member fixed with respect to said chassis and a second member hinged for rotation with

respect to said first member, said members being adapted to receive therebetween a holding collar of a filter bag, and means affixed to said door and engaging said second member when said door is in its closed position for firmly forcing said second member against said first member whereby said collar may be secured therebetween.

2. A vacuum cleaner comprising a chassis having an air intake manifold including means defining an air inlet and an air outlet, means defining a filter bag compartment adjacent said outlet and adapted to receive filterable air therefrom, a mechanism adapted for the insertion and removal of a filter bag having an inlet orifice within and from said compartment comprising a door within the outer wall thereof adapted to be rotated outwardly from the body of said compartment, a vise mechanism for holding said filter bag within said compartment comprising a 20 first member fixed with respect to said chassis,

and a second member hinged for rotation with respect to said first member, said members being adapted to receive therebetween a holding collar of said filter bag and constructed and arranged 5 to align said orifice with said outlet, and means affixed to said door and engaging said second member when said door is in its closed position for forcing said second member against said first member whereby to secure said collar therebetween.
